TERMINAL CLAMPING DEVICE

Floyd S. Green, St. Louis, Mo., assignor to Frank
 Adam Electric Co., St. Louis, Mo., a corporation
 of Missouri

Application December 1, 1932, Serial No. 645,149

10 Claims. (Cl. 173—324)

This invention relates to terminal clamping devices, and more particularly to an improved clamping mechanism for securing and electrically connecting a terminal portion of an electrical device, such as a cartridge type fuse, to a complementary terminal element of an electric circuit, or other electrical device to be associated therewith.

The principal object of the present invention is to provide an improved clamping device, of a particularly rugged and simple structure, which is adapted to effectively secure, and electrically connect a terminal portion of an electrical device to a terminal contact element of an electrical circuit, or other electrical device, and in which the clamping action is obtained by an eccentric cam mechanism, so formed and assembled as to result in a secure binding and positive electrical contacting of the associated terminal contact elements.

Another object is to provide an improved quick acting terminal clamp device for fuse terminals and the like, in which the clamping or releasing action of the device may be readily and easily effected by a simple actuation of a manual control element through a relatively small angle of rotation.

A further object is to provide a terminal clamping mechanism in which the movable head, or clamping element of the mechanism, engaging the terminal portion of a fuse or other electrical device, is formed to present a resilient terminal contacting portion to compensate for any difference in the expansion characteristics of different metals, as the terminal engaged by the contacting portion of the clamp mechanism may not be necessarily of the same material as that of the clamp contacting portion of the clamping element.

Further objects and advantages will appear from the following detailed description of the invention, and from the appended drawing, in which:

Fig. 1 is a side elevation of a preferred form of terminal clamping device, as applied to an end terminal of a cartridge type fuse, and a fixed terminal of an electric circuit; Fig. 2 is a side elevation of the preferred form of clamping device in its open, or terminal receiving position; Fig. 3 is an enlarged sectional elevation, as taken along line 3—3 in Fig. 1; Fig. 4 is an end elevation of the clamping device showing a modification of a portion thereof; Fig. 5 is a side elevation of a modified form of terminal clamp, adapted to receive terminals of cylindrical or ferrule form,

and Fig. 6 is an end elevation of the modified clamp, as viewed from line 6—6 in Fig. 5.

Referring to the drawing by reference numerals, 10 designates, generally, a terminal clamp assembly, including an angulate support or base member 12 formed of copper, or any other suitable material having good electrical conducting qualities. An end portion 14 of the base member is provided to seat on any suitable mounting 16, and is secured thereon preferably by a bolt or 10 stud 18 and nut 20. The stud 18 serves, in addition, to secure in electrical contact with the end portion 14, a terminal lug 22 on one end of a conductor 24, the other end of the conductor being suitably connected to an electrical device (not 15 shown), or associated with an electrical circuit (not shown). The opposite end portion 26 of the support 12 is formed as a contact seat for a terminal end of an electrical device, such as a standard cartridge type fuse, a portion 28 of 20 which is shown in Fig. 1 with its terminal member or blade 30 in contact with the seat portion 26. A rotary clamping head for holding the terminal 30 in electrical contact with the contact seat 26 will be presently described. 25

It is to be understood, of course, that the end portion 14 of the base member 12 may be secured directly to a terminal portion of an electrical device, thus eliminating the connector lug 22 and conductor 24, or the end may be modified to form 30 a stationary contact element of an electric switch (not shown).

A clamping mechanism support 32, consisting of a base portion 33, having an extended arm 34 at each end thereof, is secured, as by rivets 36, 35 to a portion 38 of the base member 12, adjacent the end 26 thereof. As shown in Figs. 1 and 3, the arms 34 extend from the base 33 toward the end of the base portion 26, and are provided, adjacent their outer ends, with a bearing aperture 40 for a pivot pin or shaft 42 disposed between the arms, the ends 44 of the shaft being extended beyond the arms 34, as best appears in Fig. 3. Pivotedly seated upon each shaft end 44 is an eccentric disc cam 46, and a circularly expanded 45 end portion 48 of an arm 50 of a substantially U-shape disc actuating handle or lever 52. Each disc 46, which has a smaller diameter than that of the circular arm portion 48, is centrally positioned on the arm portion, and is secured thereto 50 by any suitable means, such as a rivet 54. As will be noted in Fig. 1, the end of the shaft 42 engages the circular arm portion 48 inwardly of the end thereof, and is radially displaced from the center 56 of the section. The axis of the 55

- shaft is preferably offset from and parallel to a plane passing through the centers 56 of the sections 48 and the longitudinal center line of the handle arms 50.
- 5 A substantially U-shape terminal clamping member or jaw 58 is provided with a suitable aperture 60 adjacent the end of each of its arms 62 to receive, in the manner of an eccentric strap or follower, one of the aforementioned eccentric 10 cam discs 46. The clamping member 58 is free to rock or oscillate about the disc bearings, between the handle arms 50 and the sides of the contact seat portion 26, to permit ready adjustment between the clamp and the terminal portion 15 engaged thereby and is adapted to be actuated by the discs and operating handle 52, as will be more fully explained hereinafter. The cross member or head portion 64 of the clamp 58 is preferably formed as shown in Fig. 3, to present 20 a large clamping surface, and to give some resilience to the clamping member so as to allow for any difference in expansion between the clamping head and the metallic terminal element engaged thereby. Or, as shown in Fig. 4, the head 25 portion 64 of the clamp 58 may be formed to give a greater flexibility to the head portion, but at a sacrifice of clamp contacting surface. Of course, it is to be understood that the head portion may be formed in a rigid manner, if it is so desired, but 30 such rigid construction may result in a binding of the clamp and terminal element engaged thereby, which may, in many instances, cause considerable trouble in the removal of the terminal element from the clamping device.
- 35 Figs. 5 and 6 illustrate a modification in the terminal clamping device, adapting it to terminal ends of electrical devices which are of cylindrical or ferrule form, such terminals being found, particularly, in the electrical fuse art.
- 40 The clamping mechanism support 32 of Figs. 1 and 3, is replaced, in the modified device, by a member 68 secured as by a bolt 70, to one end of a base 72, the other end of the base (not shown) being connected to an electrical device, or a conductor 24 and connector lug 22, as shown in Fig. 45
1. The end 74 of the member 68 is inwardly, arcuately depressed, as at 76, to form a contact seat for a cylindrical terminal 78 of an electrical device, such as a cartridge fuse 80. The member 50 68 operatively supports a modified clamping element or head 82, and actuating mechanism therefor similar to the mechanism described hereinabove, and illustrated in Fig. 3. The contacting portion 84 of the clamping head 82 is 55 outwardly expanded in an arcuate manner, corresponding to the arcuate seat portion 76 of the support 68, to adapt it to the cylindrical terminal 78 of the fuse 80.
- 60 In the operation of the clamping device, the jaw elements 58 and 26 are placed in terminal receiving position by operating the handle 52 in a clockwise manner, as illustrated in Fig. 2. As will be understood from the eccentric cam mounting of the clamping element, as the head 65 portion 64 moves away from the terminal seat 26, a transverse displacement of the clamping element necessarily occurs which moves the element nearer the outer end of the seat portion 26. With the clamping device in open position, 70 the terminal end 30 of the fuse 28 may be inserted between the head portion 64 and the seat 26, in contact with the terminal seat portion. The handle 52 may now be actuated to the left (Fig. 1) to the position shown in the 75 figure, thus bringing the clamping head firmly

into clamping engagement with the terminal 30. It will be noted that the clamping operation is essentially that of a crank or toggle mechanism. As the head engages the surface of the terminal, a sliding movement occurs in a right hand direction (Fig. 1), which results in a clean electrical contact between the head and the terminal, the clamping element serving as an auxiliary electrical conductor to the base member 12. To release the terminal, and hence the fuse device, the handle 52 is actuated to the right (Fig. 2) which lifts the head portion 64 from its clamping engagement with the terminal. A like clamping and releasing action occurs with the modified clamping device of Figs. 5 and 6. 15

5 It is to be understood that the clamping device illustrated in Figs. 1 to 4 may be applied to the terminal ends of electrical bus bars which are of flat form, and rectangular in cross section, or to any type of electrical cable or conductor 20 having, at least, a flat terminal end portion. The modified clamp shown in Figs. 5 and 6 may be applied, in a like manner, to the terminal end portion of bus bars or conductors of circular cross section. Although the clamping device is primarily adapted to be applied to terminals of electrical devices or conductors, it may be used, with equal effect, in purely mechanical structures.

30 The clamping mechanism described hereinabove forms a simple, rugged, and durable clamp which may be applied to the terminal ends of electrical devices, or electrical conductors, for mechanically securing them, and electrically associating them with other electrical devices, or 35 in circuit relation with a desired electrical circuit.

It is to be understood, of course, that the embodiments of the invention herein described in detail are not to be considered as limiting the invention, but that substantial alterations and 40 modifications may be made in the structure or operation thereof without departing from the full intended scope of the invention, as defined in the claims appended hereto.

45 I claim:

1. In a quick acting clamping device for an electrical conductor, a pair of conductor gripping elements, one of said elements being of hollow form and overlying the other element, a rockable operating member overlying the said hollow element, pivoted to said other element, and a plurality of cam discs secured in spaced relation on said operating member, said discs supporting said hollow element for rockable and shiftable movement, with respect to said other element, upon manual actuation of said operating member.

2. In a clamping mechanism for a terminal element of an electrical device, a base including a contact seat for the terminal element, an operating member pivotally carried by said base a resilient clamping element for engaging said terminal element, and supporting means for said clamping element, said means including a cam element on said operating member, the cam and 65 operating member coacting for actuation of said clamping element.

3. In a clamping mechanism for a terminal element of an electrical device, an angulate base for said mechanism, said base including a contact-engaging portion for the terminal element, a pivot on said base, an operating lever carried by said pivot and having a cam element near one end thereof, and a clamping element about said 70 75

- contact-engaging portion, supported by said cam element for shiftable and rockable movement, with respect to said contact-engaging portion, upon actuation of said operating lever.
5. In a clamping mechanism for a terminal element of an electrical device, a base including a terminal seat, a pair of arms on said base, an operating member pivotally carried by said arms, an eccentric cam disc on said member, and a clamping element operatively supported by said operating member and cam disc for actuation thereby.
6. In a clamping mechanism for a terminal element of an electrical device, a base including a terminal seat portion on one end thereof, arm members adjacent said seat portion, an operating lever pivotally carried by said arms, eccentric cam discs near one end of said lever, and a terminal clamping member pivotally carried by 10 said cam discs for actuation thereby into clamping or releasing positions, with respect to said terminal element, upon pivotal movement of said operating lever.
7. In a clamping device for a terminal end of an electrical apparatus, a base including a terminal contact seat on one end thereof, spaced bearing arms on said base adjacent said contact seat, an operating lever pivotally supported by said arms and having eccentric cam discs in 15 opposed, spaced relation thereon, and a substantially U shaped clamping element having an aperture in each leg portion to receive said cam discs, whereby the clamping element is operatively associated with said operating lever for 20 engaging said terminal end.
8. In a clamping mechanism for a terminal element of an electrical device, a base including a terminal contact seat, a pivot on said base, an operating lever carried by said pivot, said lever having eccentric cam discs disposed in spaced relation thereon, and clamping means for said terminal, said means including a resilient clamping head and cam followers operatively engaging said cam 25 discs, said clamping means being associated with said lever and cam discs, for independent pivotal movement thereon.
9. In a clamping mechanism for a terminal element of an electrical device, a base including a terminal contact seat, a pivot on said base, an operating lever carried by said pivot, a cam carried by said operating lever, and clamping means for said terminal including a cam follower engaging said cam, said clamping means being operatively 30 associated with said cam for independent pivotal movement thereon.
10. In a clamping mechanism for a terminal element of an electrical device, a base of angulate form having a terminal seat portion on one end thereof, a pivot, and a supporting member therefor on said base, said supporting member being disposed adjacent to, and beneath said terminal seat portion, an outer U shaped actuating member having its leg portions seated on said pivot, an eccentric cam disc near the free end of each leg portion of said actuating member, an inner U shaped actuated member having a resilient clamping head portion and having an 35 aperture in each leg portion to receive said cam discs, the apertured legs of said actuated member forming eccentric cam followers, whereby actuation of said outer member is adapted to effect distance adjustment between said inner member and seat portion, for detachably clamping thereto a terminal of an electrical device.

FLOYD S. GREEN.
